[57] CLAIM

The ornamental design for a vehicle seat mounting mechanism, as shown and described.

DESCRIPTION

FIG. 1 is a top plan view of a vehicle seat mounting mechanism showing our new design;

FIG. 2 is a bottom plan view thereof;

FIG. 3 is a side elevational view thereof;

FIG. 4 is a rear elevational view thereof;

FIG. 5 is a front elevational view thereof;

FIG. 6 is a top plan view with the mechanism in an open position thereof;

FIG. 7 is a bottom plan view with the mechanism in an open position thereof;

FIG. 8 is a top perspective view with the mechanism in an open position thereof;

FIG. 9 is a top perspective view thereof;

FIG. 10 is a bottom perspective view thereof; and,

FIG. 11 is a bottom perspective view with the mechanism in an open position thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.
